UNITED STATES PATENT OFFICE.

LOUIS BRAND, OF LOS ANGELES, CALIFORNIA.

PICTURE-FRAME.

SPECIFICATION forming part of Letters Patent No. 759,840, dated May 10, 1904.

Application filed October 28, 1902. Serial No. 129,180. (No model.)

To all whom it may concern:

Be it known that I, LOUIS BRAND, of Los Angeles, in the county of Los Angeles and State of California, have invented a certain 5 new and useful Improvement in Picture-Frames, of which the following is a full, clear, and exact description, reference being had to the annexed drawings.

This invention, which relates to certain improvements in picture-frames, has for its object to enable any picture-frame to be used for holding pictures of different sizes; and the invention consists in constructing such frames of parts which fit into each other with 15 frictional contact in such manner that the several parts are capable of being slid upon each other lengthwise, while maintaining the rectilinear form of the frame, so that the frame may be adjusted to fit pictures of different 20 dimensions and of different proportions of length or width.

Upon the annexed drawings, Figure 1 is a front elevation of a picture-frame constructed according to my invention, the dotted portion of the figure representing one of the enlargements of which the frame is capable. Fig. 2 is a side or edge elevation corresponding to Fig. 1, the dotted portion corresponding to the enlargement shown dotted in Fig. 30 1. Fig. 3 is a horizontal section on the line *a a*, Fig. 1, the dotted portion corresponding to the enlargement shown dotted in Fig. 1. Fig. 4 is an enlargement and exaggerated transverse section of one side or member of 35 the adjustable picture-frame whose parts or members are of a triangular cross-section. Fig. 5 is a transverse section of one side or member of the adjustable picture-frame whose section is a square. Fig. 6 is another transverse section of one side or member of the 40 adjustable picture-frame of molded form. Fig. 7 is an end elevation of the fastening device and ornament-carrier of my adjustable picture-frame.

45 As shown by Figs. 1, 2, 3, and 7 of the drawings, my picture-frame consists of hollow metallic tubular parts, respectively marked A B C D, each of which consists of two members at right angles to each other 50 and united at right angles to each other by

the miter-joints E, as shown at each corner of the frame. The metal of which these tubular parts or members are constructed is thin and drawn or rolled into circular or cylindrical or other sections of such dimension 55 that the parts or members which are slid upon or into each other fit closely, but with such sufficient frictional freedom for being moved upon each other that a picture-frame so constructed is readily adjusted to any dimension 60 required by pulling or pushing the slideable parts thereof either lengthwise or transversely, or both lengthwise and transversely, until the frame has been adjusted to the dimensions requisite for containing any picture 65 or other representation or printed or written matter which it may be required to place in such frame. The inner part of each side member and of the top and bottom members of the frame have a continuous parallel opening 70 L (shown at Fig. 3 and in the enlarged sectional views Figs. 4, 5, and 6) formed in them to receive the picture, as indicated in Fig. 3 by the line F, also the back-board G and the sheet of glass H when the picture is glazed; 75 but the sheet of glass may or may not be used, as desired.

It is not possible to represent in section in the drawings the inner and outer tubes of which my improved frame is constructed as 80 in sliding contact with each other, and for this reason the inner and outer tubes in Fig. 3 are represented with the thin black circle between them; but it is to be understood that this space does not actually exist in my picture-frame as 85 practically constructed. It is further to be understood that with the view of enabling the frame to be rigidly maintained in any adjusted dimensions the fastening device, consisting of the ring I and its thumb-screw J, upon 90 the outer tubes of each side of the frame is used. Each ring I has an opening across it corresponding with the opening L, through which the picture F, back-board G, and glass H pass, and by tightening the thumb-screw 95 J of each such ring I the tubes of the frame which it embraces are pinched or held tightly in any adjusted position and are capable of being slid to and fastened at the center of each side of the frame in all positions of ad- 100

justed dimensions of the frame, also of holding the ornaments M, which are covered by the rings I, at the center of each side of the frame, thereby rendering the whole symmetrical. Each of the pinching-screws has a hole *e* in it, through any two of which opposite holes the ends of a suspension-cord are fastened for hanging the picture-frame, or my improved frame may be supported by an adjustable prop or easel-bar N, as shown at Figs. 1 and 2.

When the improved picture-frame is used for resting upon any flat surface—such as a table, counter, or other support—and for being supported by an easel-bar, its corners are provided with points *e*, which engage with any such flat surface sufficiently to prevent the frame from slipping thereon.

Having now described my invention, what I consider novel and original, and therefore claim to be secured to me by Letters Patent, is as follows:

1. A picture-frame of slidably-movable parts or members, the opposite slidable parts being parallel and the adjacent slidable parts at right angles to each other, each sliding

member consisting of two tubes of thin metal, one within the other, and having a longitudinal opening or slit throughout the inner edges of the horizontal and vertical members, the sliding parts having miter-joints, and being held together in any adjustable position by frictional contact of the sliding parts substantially as hereinbefore described.

2. A picture-frame consisting of slidably-movable parts or members, each part or member consisting of two tubes of thin metal, one within the other, and having longitudinal openings or slits at the inner edges, the rings each having a transverse slit and a pinching-screw for each ring, the sliding parts being held tightly together in any adjustable position by said rings and screws, substantially as hereinbefore described.

In testimony whereof I have hereunto set my hand, this 30th day of July, A. D. 1902, in the presence of two subscribing witnesses.

LOUIS BRAND.
